DISTRIBUTING DEVICE

Application filed September 6, 1928. Serial No. 304,368.

This invention relates to distributing devices, and more particularly to a construction which is arranged to distribute pulverized material uniformly to a pair of conduits.

In transporting pulverized material in a fluid current through a pipe line, it is found that the material and particularly the coarser particles thereof tend to segregate in the bends because of the action of centrifugal force. When therefore the main pipe line opens into a pair of branch lines, great difficulty is experienced in dividing the stream equally between the branches, since centrifugal force tends to throw the majority of the material and particularly the coarser particles thereon into one branch, and the other branch receives but little. Such difficulties have frequently arisen in the burning of pulverized coal. The pulverized coal is taken from a storage bin or directly from one or more pulverizers and transported through a conduit in a current of air. In many installations the coal stream is divided and sent through branch pipes, each leading to a separate burner. It is necessary for efficient operation that each of the burners receive the same quantity and fineness of coal, but this result is difficult to attain since there are almost invariably one or more bends in the pipe line which produce segregation of the coal anterior to the division point. Moreover, the problem is rendered even more difficult because the space in front of the furnace is usually limited and the piping must be made as simple and free from complications as possible.

If the discharge pipes are so arranged relative to the inlet pipe that the plane of the bend of the supply pipe is at right angles to the plane of the discharge conduits, i. e., the plane defined by their center lines, then no serious problem is presented, since the material will tend to divide evenly between the two discharge pipes. If, on the other hand, these planes are at less than a right angle, then centrifugal force acting upon the material tends to throw it towards

one of the discharge pipes and so causes uneven distribution of the material.

It is accordingly one object of my invention to provide a construction which will ensure a uniform distribution of pulverized material from a supply conduit to a pair of branch conduits, and particularly where the plane of the bend of the supply conduit is at less than a right angle to the plane of the discharge conduits.

It is a further object of my invention to provide a distributing device which will be adaptable to various installations, and which will operate satisfactorily without the necessity for adjustment and regardless of the size of the angle between the supply conduit and the plane of the branch conduits.

With these and other objects in view, as will be apparent to those skilled in the art, my invention resides in the combination of parts set forth in the specification and covered by the claims appended hereto.

In accordance with my invention, I provide a supply conduit arranged to deliver a stream of pulverized material in a fluid current to a pair of discharge conduits leading to points of use or deposit. In order to assure an equal division of the pulverized material between the discharge conduits, I provide a pipe system which serves to divide the incoming material into two parts and deflects a portion of each part into the other to form two streams which pass into the discharge conduits. This is preferably accomplished by dividing the incoming material into localized portions which are directed to the outlet conduits in such a manner as to distribute the material uniformly. Since the segregated or more concentrated portion of the incoming material may be located at any point in the inlet pipe, depending upon the direction of a bend in the supply conduit or other considerations, it is desirable to have the incoming material subdivided throughout the circumference of the pipe into localized portions which may be re-mixed as two streams of uniform fineness characteristics. For this purpose I may provide walls forming scoops separated by passages which serve to scoop

out localized portions of the incoming stream and conduct them to a position where they may be recombined with the remaining material to get a uniform mixture. This is 5 preferably accomplished by providing two concentric pipes having diametric partitions therein, and the scoops are arranged to catch spaced portions of the material that would normally pass between the pipes. The 10 scooped material passes within the inner pipe on opposite sides of the partition, and this partition is so shaped, and preferably as a helix, that it will transpose the scooped material coming from one side of the supply 15 conduit to the opposite side of the pipe and cause it to mingle with the material passing directly through the passages between the scoops on such opposite side of the pipe.

Referring to the drawings illustrating one 20 embodiment of my invention, and in which like reference numerals indicate like parts,

Fig. 1 is a perspective view of my device as constructed for use in a cylindrical supply conduit;

25 Fig. 2 is a perspective view of the helical partition removed from the remainder of the device;

Fig. 3 is a cross section through the center of a pipe system equipped with my device, 30 the helical partition being shown in full for clearness of illustration;

Fig. 4 is an enlarged view taken on the line 4-4 of Fig. 3; and

Fig. 5 is a view on a small scale showing 35 the exterior construction of the two-way valve.

In the drawings I have illustrated a supply conduit comprising a pipe bend 10 connected to a straight cylindrical inlet pipe 40 section 11. The pipe 11 leads to a Y-fitting 12, to which are connected a pair of branch pipes or outlet conduits 14 and 15.

In order that one only of the branch conduits may be used if desired, I preferably 45 provide a blade 16 (Fig. 3) which is pivotally mounted within the Y-fitting 12 about an axis perpendicular to the plane of the branch conduits. This blade is thus between the branch conduits and may be adjusted by 50 means of an external handle 17 (Fig. 5) so as to throw the entire stream into either branch. When both branch conduits are in use, the blade 16 is placed in a central 55 position.

The pulverized material to be distributed may come to the pipe 10 from any suitable source, such as a storage bin, or a pulverizer which is adapted to reduce the material to 60 a fine powder and deliver it on a current of air. One type of machine which is suitable for this purpose is shown in the U. S. patent to Andrews No. 1,646,720. The branch conduits 14 and 15 may lead to 65 points of deposit or use, such as storage bins,

or, if the system is used to handle pulverized fuel, to separate furnace burners.

The construction as so far described is subject to certain serious disadvantages which are overcome by my invention. Because of the action of centrifugal force, the pulverized material will tend to separate from the air as it passes through pipe bend 10 and the other bends which are usually present in the pipe line leading thereto. As 70 a result of this segregation, most of the material will flow downwardly along the right side of pipe 11 in Fig. 3 and thus pass into branch 15. It is impossible to entirely obviate this trouble by an adjustment of 75 the blade 16, since the coarse particles of material segregate more than the fine particles. While blade 16 might possibly be adjusted to equalize the quantities of material passing to the branch pipes, such adjustment could not prevent most of the coarse material from passing to branch 15, which would be particularly undesirable in the case of pulverized fuel. Furthermore, 80 if the blade 16 is adjusted away from its center position in an attempt to equalize the quantities of fuel, an unequal division of the air flow will result, thus causing different proportions of fuel and air in the two 85 branch pipes.

90 In order to overcome these difficulties, I provide the construction illustrated in Fig. 1, which is made of the proper size to fit closely in the interior of pipe 11. This device 95 comprises a central cylindrical pipe 19 considerably smaller in diameter than pipe 11. A series of baffle walls are provided to form 100 pockets or scoops 20 having steeply sloping bottoms 21 and upstanding sides 22, and these 105 are arranged around the outer circumference of the pipe 19. These scoops are so constructed as to catch small localized portions 110 of the incoming material and discharge them into the central pipe 19. The scoops are spaced apart, as shown in Figs. 1 and 4, to form passages which permit a 115 part of the material to flow into the annular space outside the pipe 19. This annular space is divided into two parts by a thin vertical partition 24 of a width substantially 120 equal to the internal diameter of pipe 11. The device is placed concentrically within the pipe 11 with the partition 24 in the same plane as the blade 16 when the latter 125 is in its mid-position. Any suitable means 130 may be utilized to hold the construction in position, such as a pair of lugs 25 extending inwardly from the pipe 11.

Within the pipe 19 I arrange a helical or deflecting partition 26 which is twisted through an angle of 180 degrees, and located with its top or inlet and its bottom or outlet edges in the same plane as the partition 24. This helical plate may be made 135 integral with the pipe 19 if desired, but for 140

convenience in manufacture I prefer to make it separate therefrom and to provide a pair of lugs 28 near its upper edge which fit in notches 29 in the pipe 19. The lower edge 30 of the pipe 19 is preferably shaped to follow substantially the curves of the two helices on the member 26, as shown in Fig. 1, in order to save weight and afford a free exit for the material flowing there-
10 through.

The operation of my invention will now be apparent from the above disclosure. A stream of pulverized material and air is introduced into the inlet conduit 10, and seg-
15 regation occurs in this stream because of centrifugal force as it passes around any bends that may be present. In the form il-
lustrated, the tendency is for most of the material to flow into the outlet branch 15, but the scoops 20 take out localized spaced portions of this material flowing near the circumference of the pipe 10 and deliver it into the central pipe 19, as shown by the arrows in Fig. 4. The material thus scooped
20 out of the stream flows along the helical partition 26 and is delivered to the oppo-
site branch pipe from that which it would otherwise have reached. The inner pipe 19 is open ended and communicates with the
25 space at the lower end of pipe 11. Hence that portion of the material flowing in the left hand side of pipe 10, as seen in Fig. 3, which is caught by the scoops 20, is trans-
posed by the helical deflecting baffle or par-
30 tition 26 to the opposite or right hand side of the device and there mixed with material coming through the passages between the
35 scoops on the right hand side of the parti-
tion 26, and this mixture flows out through
40 the right hand outlet branch conduit 15. Similarly, the material scooped from the right hand side of the pipe 10 is mixed with material flowing through the passages be-
45 tween the scoops on the left hand side and the mixture goes to the outlet pipe 14. The
50 scoops 20 and pipe 19 provide walls which form two streams, one inside the pipe 19 and one outside the pipe, and the partitions 26 and 24 divide these streams respectively
55 into two portions. Partition 26 is shaped to deflect each portion of the inner stream into a portion of the outer stream and cause these portions to mingle.

Having thus described my invention, what
55 I claim as new and desire to secure by Letters Patent is:—

1. A distributing device comprising an inlet pipe for air and pulverulent material, two branch conduits connected therewith, 60 walls interposed in the inlet pipe serving to scoop spaced portions of the incoming material from the remainder and form two streams, and partitions separating each stream into two portions, one of said parti-
65 tions being shaped as a deflecting baffle ar-

ranged to combine one portion of each stream with a portion of the other and conduct the same to the branch conduits.

2. A distributing device comprising two concentric pipes, a partition between the pipes, a partition within the inner pipe, and walls forming spaced scoops between the pipes arranged to separate and feed alternate portions of the incoming material to the inner pipe, said partition within the inner pipe being arranged to deflect the material on each side thereof into the material on the opposite side of the outer pipe.
70
75

3. A distributing device comprising an inlet pipe, two branch outlet conduits, and walls forming localized passages arranged circumferentially of the pipe and connected alternately with the two outlet conduits.
80

4. A distributing device comprising two concentric pipes, an inlet pipe connected therewith to supply a stream of air and pulverulent material, two branch outlet pipes, and baffle walls between the concentric pipes arranged to form a plurality of passages, alternate passages being connected with one outlet pipe and the remainder with the other outlet pipe.
85
90

5. A distributing device comprising an inlet pipe, two branch outlet conduits, walls forming localized passages arranged circumferentially of the inlet pipe, and means including a helical wall to conduct the material in alternate passages on one side of the pipe and cause it to mix with the material in alternate passages on the other side of the pipe and flow into one of the outlet conduits.
95
100

6. A distributing device comprising an inlet pipe, two branch outlet conduits, walls forming localized scoops separated by passages arranged circumferentially of the pipe, and means including a helical wall to conduct the material from the scoops on one side of the pipe and cause it to mix with the material in the passages located on the opposite side of the pipe and flow into one of the outlet conduits, the remaining material being delivered into the other outlet conduit.
105
110

7. A distributing device for a stream of pulverized material and air comprising an outer pipe, an inner pipe arranged centrally therein, an inlet conduit supplying material to said pipes, scoops between the pipes which are spaced apart and arranged to transmit the material caught thereby into said inner pipe and to permit other material to pass unobstructedly into the annular space around the inner pipe, a baffle wall within the inner pipe dividing the same into two spaces, a baffle wall dividing the annular space around the inner pipe into two spaces, the inlet ends of said baffle walls being located in substantially the same diametrical plane and the inner baffle wall being so shaped that it will transpose the material
115
120
125
130

within the inner pipe from one side of said diametrical plane to the opposite and cause it to mingle with the material passing unobstructedly between said scoops, and a branch outlet conduit connected with said pipes at each side of said diametrical plane to receive the material passing through the pipes.

8. A distributing device for air and pulverulent material comprising a bent supply conduit and two branch outlet conduits so arranged that the plane of the bend of the supply conduit is at less than right angles to the plane of the discharge conduits, a pipe between said conduits, walls associated with said pipe to form localized passages arranged circumferentially thereof, and means for conducting material from alternate passages to one outlet conduit and from the intermediate passages to the other outlet conduit.

Signed at Worcester, Massachusetts, this 5th day of September, 1928.
